CLAIM

The ornamental design for clamp-on holder for led lamp, as shown and described.

DESCRIPTION

FIG. 1 is a perspective view of a clamp-on holder for led lamp showing our new design;

FIG. 2 is a plan view thereof;

FIG. 3 is a front view thereof;

FIG. 4 is a bottom end view thereof;

FIG. 5 is a left side view thereof, the right side being a mirror image thereof;

FIG. 6 is a rear view thereof;

FIG. 7 is a sectional view taken substantially along line 7—7 of FIG. 3; and,

FIG. 8 is a cross-sectional view similar to FIG. 7, but with an LED lamp and a pipe on which the holder is mounted shown in broken lines for illustration only.

FIG. 1

FIG. 2

FIG. 3
